UNITED STATES PATENT OFFICE.

JAMES C. BROYLES, OF BIRMINGHAM, ALABAMA; MRS. CELESTE V. BROYLES ADMINISTRATRIX OF JAMES C. BROYLES, DECEASED.

GUN.

Application filed June 9, 1924. Serial No. 718,867.

To all whom it may concern:

Be it known that I, JAMES C. BROYLES, a citizen of the United States, residing at Birmingham, in the county of Jefferson and State of Alabama, have invented certain new and useful Improvements in Guns; and I do hereby declare the following to be a full, clear, and exact description of the invention, such as will enable others skilled in the art to which it appertains to make and use the same.

This invention relates to improvements in guns, and more particularly to such as are provided with a plurality of barrels or cylinders through which charges are to be fired, such as a double barrel shot gun, and the object in view is the improvement of the trigger mechanism for enabling the control, selectively and consecutively, of the firing means by the employment of a single trigger.

A more detailed object is the safeguarding against unintentional or accidental firing of the second barrel incident to involuntary second pulling of the trigger after first firing.

With these and further objects in view as will in part hereinafter become apparent and in part be stated, the invention comprises certain novel constructions, combinations and arrangements of parts as subsequently specified and claimed.

In the accompanying drawings,—

Figure 1 is a view partly in side elevation and partly in vertical section of a gun incorporating an embodiment of the features of the present invention, a part of the stock being broken away and omitted for facilitating clearness of disclosure, and a fragment of the barrel being broken away for the saving of space, the parts being seen on the scale of the actual size of an ordinary commercial gun, the parts being shown in full lines in the position immediately after cocking.

Figure 2 is a similar view of the same looking from the opposite side.

Figure 3 is a horizontal section taken approximately on the planes indicated by line 3—3 of Figure 1, and looking downward, the parts being shown on a magnified scale and in the position seen in Figure 1, the selective mechanism being set for first firing the righthand barrel.

Figure 4 is a vertical section taken on the plane indicated by line 4—4 of Figure 3,

parts being seen in elevation and parts omitted for clearness, the parts being in the position just before firing.

Figure 5 is a similar view of the same with the parts in the position while or immediately following firing of the righthand barrel and before the trigger is released. 60

Figure 6 is a similar view of the same with the parts in the position after such firing and after the trigger is returned to position for enabling firing of the other barrel. 65

Figure 7 is a fragmentary, vertical section taken approximately on the plane indicated by line 7—7 of Figure 3, parts being omitted for clearness of disclosure, and the parts being shown in the position seen in Figure 3. 70

Figure 8 is a detail elevation of the trip block detached.

Figure 9 is a transverse section taken on the plane indicated by line 9—9 of Figure 4. 75

Figure 10 is a transverse, vertical section taken approximately on the plane indicated by line 10—10 of Figure 1, and looking in the direction indicated by the arrow. 80

Figures 11 and 12 are detail views of the trigger and selective slide detached.

Specifically as illustrated, the embodiment of the invention shown is applied to an ordinary double barrel shot gun to which it is especially well adapted, it being one of the objects of the invention to enable the application thereof to such a double barrel shot gun as is already in use by the substitution of a selective firing slide for one of the triggers, and the substitution and addition of certain other parts as hereinafter described in detail. For the sake of brevity and avoidance of unnecessary discussion and unnecessary drawing, the details of the firing mechanism of the shot gun are omitted, such details being well known to those skilled in the art, the same firing mechanism being employed and being controlled by the same sears modified only in their rear end construction for adaptation for use in connection with the other parts of the shown embodiment of the invention. 95

With this understanding, referring to the drawings by numerals, 1 indicates the stock of a double barrel shot gun containing the ordinary firing mechanism controlled by the present improved trigger mechanism, and to the stock are hinged the usual double barrels 2 having the usual breech lock release 100

105

110

3 and safety actuator plunger 4, all of which are well known parts and operate in the usual manner. A bracket 5 upstands within the stock, being preferably fixed at its lower end to the trigger plate 6 of the stock socket, and at its upper end having an offset arm 7 which is bifurcated and a safety locking lever 8 is pivoted to and between the bifurcations. The upper end portion of the lever 8 is notched at 9 to receive and pivotally engage the slotted forward end of the operating slide 10, which extends rearwardly and is connected with the inner part of the safety slide 4 which extends through a slot 11 in the upper strap of the stock socket, and is arranged and located for manual manipulation as is usual in common practice. The lever 8 is laterally enlarged at its lower portion so as to be of a width sufficient to effectively cooperate with the parts with which it engages, as hereinafter described. The laterally enlarged portion is provided with a downwardly-extending offset web or projection 12 at its rear portion, which projection 12 has a downwardly-extending finger 13 at one side. The shoulder or end portion of the lever in front of the web 12 is provided with a depending point or lug 14 having a forwardly beveled end adapted to cooperate with the parts hereinafter mentioned.

Upstanding from the trigger plate 6 is a flat bracket 15 arranged with its faces longitudinally of the gun and commonly employed with the ordinary double barrel shotgun for carrying the trigger pivot and guiding the triggers arranged at opposite sides of the bracket. In the present improved construction, a pin 16 extends through the bracket 15 and pivotally retains the trigger web 17 in place. The web 17 extends through a slot 18 in the plate 6 in the usual manner and is provided with the usual trigger 19. The part 17 is, in fact, a relatively thin web extending vertically and longitudinally through and above the slot 18, and the upper edge of said web is cut away to form a depression or notch 20 undercut at its ends to form a forwardly-extending, open-ended slot 21, and a rearwardly-extending, open-ended slot 22, the material of the trigger web 17 upstanding above the slot 22 and being formed with an offset or shoulder 23 producing an enlargement at the open end of the slot 22. The shoulder 23 is inclined from its lower edge rearwardly and the overhanging portion of the material of trigger web 17 above the slot 22 forms a hook-like portion 24. A pin 25 is fixed to the lower portion of the rear terminus of the trigger web 17 and extends laterally to the right thereof for serving as a detent and actuator for the selective slide 26. The slide 26 consists of a sheet or web extending through the slot 27 and lying parallel to the

trigger web 17 at the opposite side of the bracket 15. The slide 26 is provided with a longitudinal slot 28 through which the respective outstanding end portion of the pin 16 extends. The slide 26 extends rearwardly from the pin and is formed with cut-away portions, leaving an upstanding projection 29 located to cooperate with one or the other of the sears hereinafter described, according to whether the slide 26 is located at the front or rear extremity of its longitudinal movement accommodated by the slot 28 in engagement with pin 16. The slide 26 extends rearwardly beyond the upstanding projection 29 and has a depending projection or lug 30 adapted to engage one side or the other of the laterally-extending pin 25. When the pin 25 engages the rear face of lug 30, the portion 31 of the lower edge of slide 26 rests upon the pin and is adapted to be lifted by the pin when the trigger is moved or pulled for effecting a firing action, and, when the slide 26 is moved rearwardly until the pin 25 engages the front face of the projection 30, the portion 32 of the lower edge of slide 26 rests upon the pin 25, so that the slide is adapted to be lifted by the movement incident to the pulling of the trigger. The parts are proportioned such that when the pin 25 engages the portion 32 of the lower edge of slide 26, the projection 29 will lie beneath and in position to operatively engage a portion of one of the sears, and when the pin 25 engages the portion 32, the projection 29 will lie beneath a portion of and in position to operate the other sear when the slide 26 is elevated by the lifting action of the pin 25 incident to a pull upon the trigger. The web comprising the slide 26 is proportioned to loosely occupy and extend through the slot in the trigger plate 6, corresponding to the ordinary trigger slot, and the plate or slide 26 is provided with a preferably knurled or otherwise suitably finished operating grip or handle 33 lying outside of and beneath the trigger plate 6, so that the operator may freely slide the plate 26 to either of its positions for bringing projection 29 into operative relation with either of the sears. Thus selective engagement of the sears by the plate 26 is provided for. It being a part of the present invention to provide that the first sear to be actuated is the one engaged by the projection 29, it is only necessary that provision be made that the other sear shall not be actuated at the time of first actuation of a sear by the projection 29, and that thereafter on the second actuation or pulling of the trigger, both sears shall be actuated to insure both successive and selective firing of the two barrels.

To this end, the sears 35 and 36 are provided with rear constructions of special location and formation, as best seen in Figure 130

3, the sears being otherwise, that is, in their forward portions, identical with the ordinary sears of a double barrel shot gun. The forward portions of the sears have, 5 therefore, not been shown, and it is understood that the firing mechanism or lock is or may be of any of the well known types influenced or actuated to operate under the actuation of said sears. Each of the sears 10 35, 36, is provided at its rear end with a lateral arm 37, 38, which arms lap each other immediately above the slide 26 and in position to have the projection 29 located beneath the arm 38 of sear 36 when the 15 slide 26 is in its rear position, that is, when the pin 25 engages the portion 32, the arm 37 being located to overhang the projection 29 and be engaged thereby when the slide 26 is in its forward position, that is, when 20 the pin 25 engages the portion 31. At the place of overlap of the arms 37 and 38, the said arms are preferably notched, as clearly seen in Figure 3, so that the cut-away portion or notch of one accommodates the projecting portion of the other, and, therefore, the two arms 37 and 38 may be and are arranged in alignment transversely of the stock so as to be readily engaged and easily underhung by a part adapted to actuate both 25 30 of the arms 37 and 38 at one time.

To effect such actuation, subsequent to the action of the projection 29 on one of the sears, a sliding trip block 39 is mounted on the trigger web 17 at the place of the notch 35 20. The sliding block 39 is provided with a longitudinal, open-edged slot 40 for accommodating the upper portion of the trigger web 17 therein, the side portions of the block 39 lying parallel to and at the sides 40 45 of the trigger web 17, or in other words, astride of said trigger web. A guiding and pivot pin 41 extends through the forward portion of the block 39 and through the slot 21 so as to enable longitudinal shifting of the block 39, and at the same time enable 50 55 pivotal movement thereof. The block 39 is notched or cut-away at 42, leaving a forward, upstanding portion and a transversely-disposed, upstanding loop 43 near the rear portion. A shoulder 44 extends rearwardly and upwardly within the notch 42 at the opposite sides of the slot 40 in position for at times underhanging the arms 37 and 38 of the sears for purposes hereinafter set forth. A rod 45 is set in a socket in the rear edge portion of the bracket 15, and is arranged on an incline extending rearwardly and upwardly into a recess in the block 39, at one side of the slot, and slightly below 60 65 the pivot 41, as best seen in Figure 8. A coiled spring 46 surrounds the rod 45 and is tensioned to stress the block 39 in a manner for pressing the block both rearwardly and in a direction for causing the rear end to tilt upward or swing upward on the pivot

41 when free to do so. A preferably transversely-square pin 47 extends through the rear portion of the block 39 below and in line with the front portion of the loop 43, the said pin extending across the slot 40 and being provided with an inclined upper surface adapted to cooperate with the shoulder 23, as hereinafter stated. It will be apparent to those skilled in the art that while the part 47 by preference, because of convenience of construction, is usually made in the form of a pin and assembled by a riveting action, the block 39 could be otherwise formed to provide the portion of the pin lying across the slot, and so long as properly shaped and located the part would function whether made in the form of a pin or made integral with the block or otherwise. Extending rearward of and below the loop 43, the block 39 is formed with projections 48, one at each side of the slot 40. The block 39 is proportioned to have that part of pin 47 extending across slot 40 lie at all times in the slot 22, either in the lower portion or in the upper portion thereof, the pin 47 being spaced from the pin 41 a distance sufficient for preventing the possibility of longitudinal movement of block 39 sufficient to enable escape of the block from the trigger web 17. As the spring 46 stresses the block 39 rearward, and at the same time tends to lift the rear end upward, the pin 47 will engage the shoulder 23 and lie in the upper portion of slot 22 whenever free to do so. The shoulder 44 is also so located that, when the pin 47 contacts with the shoulder 23, the said shoulder 44 will lie in a position forward of the arms 37 and 38 of the sears, but, when through any manipulation, the pin 47 is forced to enter the lower portion of slot 22 and caused, by the action of spring 46, to travel to the rear end of said slot 22, so that the hook 24 extends through the loop 43, the shoulder 44 will thereby be caused to lie beneath portions of the arms 37 and 38. Thus, when the pin 47 engages the shoulder 23, the block 39 may be elevated without influencing either of the sears, but, when the pin 47 has been caused to move rearwardly in the lower portion of slot 22, the shoulder 44 will engage the arms 37 and 38, and then, if the block 39 is elevated, both sears will be elevated to an operating position.

The safety-lock lever 8 is arranged to have its upper portion in line with the rear end of plunger 4, so that, whenever the release lever 3 is swung laterally for releasing the breech lock, the rearward thrust of the plunger 4 incident thereto will cause the plunger to strike the lever 8 above the pivot and shift the same to the safety position indicated in full lines in Figure 1.

In operation, the gun is cocked in the usual manner by the opening and closing of

the breech incident to which the lever 3 must be manipulated, and, as a result of which, the parts are brought to the position indicated in full lines in Figure 1. As is well known, the rear portions of the sears 35 and 36 are practically in the same positions after the gun is cocked as before, but are so adjusted that an upward movement of the rear end of either of the sears will fire the particular barrel controlled by that sear. The parts being in the position stated and the gun being cocked, the shoulder 44 of block 39 will be in front and slightly spaced from the plane of the foremost portions of the arms 37 and 38, and the selective slide 26 will be positioned with the projection 29 located beneath the arm 37, the portion 31 of the slide 26 resting on the pin 25. The lever 8 is located with its projection 12 immediately above the trigger, the reduced portion resting against the upper edge of the hook 24 while the extension 13 extends past the upper edge of hook 24 and engages one of the arms 48 of the sliding trip block 39. The parts are thus effectively held against firing or other operation than the possible shifting of the slide 26, as herein-after stated. Now, if the operator wishes to fire the righthand barrel, he merely pushes the slide 4 up forwardly along the stock socket in the usual manner of releasing an ordinary gun for firing. It is only necessary then for him to pull on the trigger 19 to fire the righthand barrel. The pull on the trigger 19, causing the trigger web 17 to swing upon its pivot 16, causes the pin 25 to lift the rear end of the slide 26, swinging the slide on its pivot 16 and thereby lifting the projection 29 sufficiently for raising the arm 37 and elevating the sear 35 to the hammer-releasing position. When the slide 4 is moved forwardly to the position for releasing the safety latch, the lever 8 moves to the position shown in Figures 4 and 5, with the projection 14 located immediately above the loop 43 of block 39, so that when the trigger 19 is pulled for effecting the firing as just described, the upward movement of the hook end 24 of web 17 carries up with it the rear end of the block 39 until the loop 43 strikes the projection 14, the loop 43 remaining in a position upstanding above the hook 24 and being actually elevated by the stress of the spring 46 plus the action of the pin 47 in having its inclined face overlap the inclined face of shoulder 23. When the upper extremity of the loop 43 strikes projection 14, the loop is held against further upward movement thereby. It will be apparent that until this contact is effected, the pin 47 will remain in the enlarged rear portion of slot 22 in engagement with the shoulder 23. This engagement is assured by virtue of the fact that the shoulder 23 is beveled or inclined,

and the rear edge of the pin 47, which engages the shoulder 23, is correspondingly inclined to cooperate therewith and be held thereby against the possibility of dropping down. The pressure of spring 46 stressing the block 39 rearwardly, and, at the same time tending to lift or elevate the rear end of the block 39, also insures retention of the pin 47 in engagement with the shoulder 23. However, during the first firing, when the trigger is pulled and the loop 43 is thus elevated to contact with the lug or projection 14, further upward movement of the rear end of the web 17, while the rear end of block 39 is held against such movement by engagement of loop 43 against projection 14, causes the hook 24 to rise above the pin 47 and brings the narrower, lower portion of slot 22 in line with the pin 47. The moment this position is reached, the spring 46 acts to move the block 39 rearwardly a very slight distance represented by the distance from the rear face of the shoulder 44 to the front face of the adjacent arms 37 and 38, this space being clearly seen in Figure 4. The shoulder 44 thus moves up into contact with the arms 37, 38, and the parts assume the position shown in Figure 5 with the extreme edge of pin 47 underlapping the extreme edge of shoulder 23. The firing occurs with the parts in this position, and then the operator releases the trigger 19 and allows the parts to drop back to the position seen in Figure 6. As the free end of the trigger web 17 is thus lowered, the shoulder 44 arrives at a position beneath the planes of the arms 37 and 38, and the sliding trip block 39 is thrust rearward by the action of spring 46 until the pin 47 strikes the rear end of the narrow portion of slot 22. The shoulder 44 thus underlying the two arms, 37, 38, will insure a lifting of both of said arms with the next pull of the trigger 19, whereby the second or lefthand barrel is fired upon the second pulling of the trigger. When the trigger has been pulled the second time, it being understood, of course, that the sears always return after a firing operation to their former position, the parts are in the position shown in Figure 6, which is identical whether after the first firing or after the second firing. It is now desirable to reload and cock the gun, and this is done in the usual manner by the operation of the lever 3 followed by the breaking, loading and restoring of the parts to the position seen in full lines in Figure 1. When the lever 3 is manipulated to release the breech lock, the plunger 4 is given a rearward thrust by mechanism not illustrated, but of the ordinary type commonly in use, and this rearward thrust causes the rear end of the plunger 4 to strike the upper portion of lever 8, which effects a swinging of the lower portion in a forward direction. The parts

starting from the position seen in Figure 6, the projection 12 engages the rear edge of the loop 43 and stresses the same forwardly against the pressure of the spring 46. As the extension 12 and finger 13 are slightly inclined forwardly and downwardly, they exert a slight upward lifting action on the loop 43, but whether this action occurred or not, they press the entire block 39 forward until the pin 47 is moved out of the lower or narrow portion of slot 22 and into position for engaging the shoulder 23, and the spring 46 stresses block 39 to lift the rear end of the block so as to bring the extreme edge of pin 47 to overlap the extreme edge of the shoulder 23, so that, when the slide 4 is moved forwardly for releasing the safety lock and the projection 12 is moved backward out of engagement with the loop 43, the block is free to move and does move slightly upward and rearward until the pin 47 is fully seated against the shoulder 23. Thus, in the first part of the cocking operation, the trigger parts are restored to their former positions with the shoulder 44 forward of and out of line with the arms 37 and 38, and the parts are again in position for another firing operation.

The gun being cocked and the parts being in the position seen in Figure 1, the operator releases the safety latch and then, desiring to fire the lefthand barrel instead of the right, presses the grip 23 rearward. This causes the slide 26 to move from a position with the portion 31 engaging pin 25 to a position where portion 32 engages the pin 25, and this brings the projection 29 from the position underlying the arm 37 to a position underlying the arm 38. Now, if the trigger is pulled, the lefthand barrel will be fired by the action of the projection 29 against the arm 38. All of the other parts remain the same as above described and function as stated. It will be noted that the shoulder 44 is disposed out of vertical alinement with the arms 37 and 38 until the first firing, and upon the completion of the trigger action incident to the first firing, the block 39 assumes the position seen in Figure 6 with the shoulder 44 underlying the two arms 37 and 38, and upon the next pulling of the trigger the righthand barrel will be fired.

As is well known to those skilled in the art to which the present invention relates, it is the common experience of operators that, after firing a gun, the trigger finger involuntarily, and in many instances unconsciously, makes a second pull upon the trigger. With a double-trigger gun or a pump gun, this spasmodic or involuntary pull is harmless, but, unless guarded against, it would in the present improved structure cause the second barrel to be fired when the operator did not wish it. The trip block 39

and cooperating parts are, therefore, especially constructed to prevent such action. Upon the firing of the first barrel, and the consequent release of block 39, said block, owing to its inertia being overcome quickly, lags in its rearward movement, and such movement is interrupted by the detent pin 47 coming into engagement with the shoulder 23. The sudden recoil of the gun causes such rearward movement of the parts as to relieve the stress of the trigger finger on the trigger and part 19 momentarily, at the time of recoil, is allowed to return to its original position, but, as the trigger finger is still pulling, not having relaxed, the operator will without intent or even knowledge of the fact cause his trigger finger to catch up with the trigger, in its position assumed incident to the recoil, and give a second pull upon the part 19. This invariably occurs in the use of firearms, and is known as the recoil pull. It happens so quickly that no marksman can prevent it. Hence, I have safeguarded against it by providing the detent pin 47 and shoulder 23 which effectively and invariably intercept the movement of block 39, and thus heads off the second or recoil pull of the trigger. The function of block 39, therefore, affords absolute assurance against any likelihood of doubling or accidental firing of the second barrel.

It should be borne in mind that, since the operating parts above described are all concealed and probably not understood by the operator at all, the guide for the operator in the matter of firing one barrel or the other is the position of the grip or handle 33. If it is located in its forward position, then the righthand barrel will be fired first when the trigger is pulled, but if the handle or grip 33 is in its rearward position, the left-hand barrel will be first fired.

The accompanying drawings illustrate and were carefully copied from an actual operative structure, it having been found desirable to magnify the showing to disclose the details and enable an accurate reading of the drawings. It will be observed also that while every part in the mechanism shown and described is made with great precision and functions exactly as required, so as to be reliable and dependable at all times, there is with practically every moving part a degree of looseness enabling ready and easy movement and the assurance of the adaptation of the part to its functions in its relation to all the other parts, and, while this looseness enables the required play for insuring ease of operation of the parts, the proportions are such as to always assure effectiveness and precision of functioning. As, for example, the projection 14 has its free end beveled off forwardly so that if, in any instance, the slide 4 should be pushed far enough forwardly, as when it is being

manually released, to allow the loop 43 to have its rear edge pass in front of the projection 14, since the said loop is free to swing upward, there will be no locking action 5 between the loop and projection 14, because a movement of either of the parts will cause a camming action between the loop and the inclined or beveled front of projection 14. This beveled front, however, does not interfere in the least with the functioning of projection 14 in retaining the loop against rising with the hook 24 under the first actuation of the trigger after cocking.

What is claimed is:—

- 15 1. In a multiple barrel gun, the combination of actuating sears, a trigger, means actuated thereby for operating one of the sears, a slide shiftable to position for operating the other sear and adapted to be actuated by said trigger for effecting operation of said other sear, means for retaining the slide out of the operative position during operation of the first sear, means for shifting the slide to the sear-operating position, a safety lever adapted to be moved to and from a position preventing movement of the trigger, and a projection on the lever adapted to engage and restore said slide to its inoperative position.
- 20 2. In a multiple barrel gun, the combination of actuating sears, a trip block having a portion at times adapted to lie out of operative relation with respect to the sears and at times to operatively engage the sears incident to a movement of the block, a trigger for actuating the block for operating the sears, means stressing the block toward an operative position, means retaining the block against movement under such stress, 25 a safety detent for the trigger located to co-operate with the slide for releasing the same, and means actuated by the trigger for actuating one of the sears independently of the action of the trip block.
- 25 3. In a multiple barrel gun, the combination of actuating sears, a trip block having a portion at times adapted to lie out of

operative relation with respect to the sears and at times to operatively engage the sears incident to a movement of the block, a trigger for actuating the block for operating the sears, means stressing the block toward an operative position, means retaining the block against movement under such stress, a safety detent for the trigger located to co-operate 50 with the block for releasing the same, means actuated by the trigger for actuating one of the sears independently of the action of the trip block, and means carried by the trigger 55 detent for restoring the trip block to its in- 60 operative position.

4. In a multiple barrel gun, the combination of actuating sears, a trigger mounted to swing pivotally relatively thereto and having a web, the web being formed with spaced longitudinal slots, and one of the slots having an offset or shouldered portion, a slotted block mounted on the trigger web with the web extending into the slot of the block, a pivot pin connected to the block and extending through one of the slots of the trigger web, a detent carried by the block and extending transversely through the other slot in position to be moved to and from engagement with the offset, a spring stressing 70 the block in a direction tending to retain the detent in engagement with the offset portion and also tending to move the detent into another portion of the slot when the detent is moved out of engagement with the offset, 75 a sears-engaging part on the block adapted to be held out of operative relation to the sears by the engagement of the detent with the offset and to move under the influence of the spring into operative relation with 80 the sears when the detent is disengaged from the offset, means actuated by the trigger for actuating one of the sears independently of the block, and means functioning upon actuation of the trigger to move the detent out 85 of engagement with the offset.

In testimony whereof I affix my signature.

JAMES C. BROYLES.
